(57) **CLAIM**

The ornamental design for a lighting fixture, as shown and described.

DESCRIPTION

FIG. 1 is a front, left and bottom perspective view of a lighting fixture showing my new design;

FIG. 2 is a rear, right and top perspective view thereof;

FIG. 3 is a front view thereof;

FIG. 4 is a rear view thereof;

FIG. 5 is a left side view thereof;

FIG. 6 is a right side view thereof;

FIG. 7 is a top plan view thereof;

FIG. 8 is a bottom plan view thereof;

FIG. 9 is an enlarged partial view of FIG. 2; and,

FIG. 10 is an enlarged partial view of FIG. 5.

The broken lines in the figures illustrate portions of the lighting fixture that form no part of the claimed design.

The dot-dash broken lines are imaginary lines that are included for reference purposes only to identify the enlarged view; the dot-dash broken lines form no part of the claimed design.
